UNITED STATES PATENT OFFICE.

JOHN F. HAWLEY, OF CHILlicothe, MISSOURI.

COMBINED RAILWAY-TIE AND RAIL-CLAMP.

1,134,130.

Specification of Letters Patent.

Patented Apr. 6, 1915.

Application filed November 10, 1914. Serial No. 871,359.

To all whom it may concern:

Be it known that I, JOHN F. HAWLEY, a citizen of the United States, residing at Chillicothe, in the county of Livingston and State of Missouri, have invented certain new and useful Improvements in Combined Railway-Ties and Rail-Clamps, of which the following is a specification.

This invention relates to certain new and useful improvements in a combined railway tie and rail clamp and has as its primary object to provide an improved construction wherein the tie will be formed of metal or of a suitable composition and wherein the rails may be readily attached to the tie to be firmly held in position thereon.

The invention has as a further object to provide an improved construction of the character referred to, wherein the use of spikes or other similar fastening devices will be eliminated and wherein the rails may be resiliently gripped in position upon the tie to consequently combine the yielding qualities of such a connection in a thoroughly efficient fastening means.

A further object of the invention, in this connection, is to provide an improved construction wherein the rails will be rigidly supported against movement in one direction and will be yieldably supported for relatively limited movement in the opposite direction. And a still further object of the invention is to provide a simple and efficient form of clamping means for connecting the rails with the tie and wherein the said clamping means may be readily attached to or detached from the tie.

With these and other objects in view, my invention will be more fully described, illustrated in the accompanying drawing, and then specifically pointed out in the claims which are attached to and form a part of this application.

In the drawing: Figure 1 is a perspective view of my improved railway tie and rail clamp, showing the rails in position upon the tie; Fig. 2 is a fragmentary horizontal sectional view, showing the arrangement of the clamping members employed; Fig. 3 is a transverse sectional view, particularly illustrating the disposition of the terminal guide lips carried by the clamping members; Fig. 4 is a perspective view of one of the clamping members detached and illustrating the parts thereof disassembled but in proper relative position; Fig. 5 is a frag-

mentary sectional view of a slightly modified form of clamping member.

Corresponding and like parts are referred to in the following description and indicated in all the views of the drawings by the same reference characters.

In the preferred embodiment of the invention, as illustrated in the drawing, the body portion of my improved tie is indicated at 10. The tie is preferably formed of metal, although, it is to be understood that any other suitable material may be employed and is preferably of hollow construction, being longitudinally recessed or channeled upon one side to provide side walls 11 which are formed with outwardly diverging confronting faces 12, as clearly illustrated in Fig. 3 of the drawing, the inner faces of the said side walls intersecting the outer faces thereof at the outer extremities of said walls to provide relatively sharp terminal edges disposed to engage within a road bed. By this arrangement, it will be observed that the tie is disposed to seat firmly within the road bed and is so formed as to counteract any tendency of the tie to creep.

Formed on each end of the tie and connecting the side walls 11 thereof, are transversely extending webs 13 which provide anchors for the clamping members employed, which will be presently described. In this connection, it is desired to state that, although I have shown the webs 13 as an integral part of the body portion of the tie, still, it is to be understood that I do not wish to limit myself to this construction as the said anchors may be detachably connected to the tie to bear over the ends of the side walls thereof, in a manner which will be readily understood.

Arranged upon the upper face of the tie, adjacent the opposite extremities thereof, are confronting upstanding abutments 14, which may be integrally formed with the tie and which are provided with longitudinal projecting and inwardly extending lips 15 disposed to engage over the base flange of each of the rails, conventionally shown at 16.

Formed in the upper wall of the tie and inwardly spaced from the abutments 14, are suitable openings 17 which, as best illustrated in Fig. 1 of the drawing, are preferably rectangular in contour and communicating at one end with each of said openings, 18, is a longitudinally extending slot 18.

Co-acting with the abutments 14 and ar-

ranged within the openings 17, are rail clamping members, indicated as a whole by the numeral 19. More particularly, each of said members is preferably formed of suitable resilient material and includes a body portion 20 upon one side of which is formed a reduced shank 21, the said shank terminating, at its outer extremity, in an elongated transversely extending head 22, the head 22 being disposed at an angle to the shank and arranged to bear over the base flange of the rail 16 opposite the adjacent abutment 14. The body portion 20 is provided with an opening 23 medially thereof and upon its side opposite the shank 21 is formed a terminal guide lip 24. As illustrated in the drawing, the guide lip 24 is preferably integral with the body portion 20 and extends laterally upon one side thereof with its outer extremity disposed in a horizontal plane passing through the opening 23. However, as illustrated in Figs. 2 and 3 of the drawing, the outer extremity of the guide lip is preferably in substantial alignment with the adjacent side of the opening 23.

The clamping members 19 are detachably connected with the tie and are arranged thereon with the shanks 21 extending through the openings 17 and with the heads 22 projecting exteriorly the tie. It will be observed that the openings 17 are of such width that the side walls thereof will engage the side edges of the shanks 21 to consequently support the clamping members laterally. In connecting the clamping members with the tie, the said members are inserted within the openings 17 and slots 18 from within the tie, the said members being turned so that the heads 22 thereof will readily pass through the said slots and openings, as will be clearly understood. The clamping members may, accordingly, be attached to or detached from the tie, as desired. When the rails are not present the clamping members will, under ordinary circumstances, be prevented from becoming detached from the tie, since the heads 22 of the said members will normally be disposed transversely of the openings 17.

Engaging the clamping members 19 and detachably connecting the said members with the anchors 13, are suitable rods 25. Each of the rods 25 is passed through the opening 23 of the adjacent clamping member and loosely through a suitable bore formed in the contiguous anchor, as best shown in Fig. 2 of the drawing, the said rods being each provided with a terminal head 26 and being screw threaded adjacent its opposite extremity to receive a nut 27.

Surrounding each of the rods 25 and interposed between the head 26 thereof and the adjacent clamping member, is a helical spring 28 which bears at one end against a suitable washer 29 loosely mounted upon the

rod and confronting the clamping member and it will be observed that, when the nuts 27 are tightened against the abutments 13, the rods 25 will be moved longitudinally against the tension of said springs to cause the springs to resiliently engage the clamping members 19 which, in turn, will be resiliently held in engagement with the rails.

Attention is now directed to the fact that, normally, the guide lips 24 will engage the rods 25 upon one side thereof to maintain the body portion 20 of each of said clamping members at substantially right angles to the rods so that, at all times, the rods may slide freely through the openings 23. This is a very important feature of the present invention since, were the guide lips 24 not present, the body portions of the clamping members, upon a tightening of the rods 25, would move into such angular relation to the rods as to cause the walls of the openings 23 to bite into the rods upon opposite sides thereof and, consequently, prevent proper adjustment of the said rods.

From the preceding description, it will be seen that the tension of the clamping members 19, upon the rails 16, may be readily regulated by properly adjusting the nuts 27 of the rods 25 and that, while the rails 16 are rigidly held against movement in one direction by the abutments 14, they are yieldably supported for movement in the opposite direction by the clamping members 19. However, it should be stated in this connection that such inward movement of the rails, against the tension of the springs 28, will be inappreciable, the main object attained being that of yieldably connecting the rods 25 with the clamping members. It will further be seen that the rods 25 may be readily removed, when desired, to effect the displacement of the clamping members 19 and that, as previously set forth, the clamping members 19 may be disconnected from the body of the tie itself, when desired.

In Fig. 5 of the drawing, I have illustrated a slight modification of the invention, wherein yieldable washers 30 are interposed between the head 26 of each of the rods and the body portion 20 of the adjacent clamping member, the said washers taking the place of the springs 28 employed in the preferred form of the invention and serving a similar function. Any desired number of such washers may be used and, of course, the said washers may be formed of any suitable material such as will meet the demands existing.

Having thus described the invention, what is claimed as new is:

1. In a device of the character described, a railway tie including a body portion provided with an abutment and formed to receive a clamping member, an anchoring member carried by the body portion, a

clamping member carried by the tie and disposed to co-act with said abutment in engaging a rail, means passing through the clamping member and operatively connecting the said member with the anchoring member, and means carried by the clamping member and engaging said first mentioned means for maintaining the clamping member at its point of intersection with 5 said first mentioned means, at substantially right angles thereto.

2. In a device of the character described, a railway tie including a body portion provided with an abutment and formed to receive a clamping member, an anchoring member carried by the body portion, a clamping member carried by the tie and disposed to co-act with said abutment in engaging a rail, said clamping member including a body portion, means passing through the body portion of the clamping member and operatively connecting said member with the anchoring member, and means carried by the body portion of the 15 clamping member and engaging said first mentioned means for maintaining the body portion of the clamping member at substantially right angles to the said first mentioned means.

3. In a device of the character described, a railway tie including a body portion provided with an abutment and formed to receive a clamping member, an anchoring member carried by the body portion, a clamping member carried by the tie and disposed to co-act with said abutment in engaging a rail, said clamping member including a body portion apertured to receive a rod, a rod passing through said aperture and operatively connecting the clamping member with said anchoring member, and a guide lip formed on the body portion of the clamping member and engaging the rod for maintaining the body portion at substantially right angles thereto.

4. In a device of the character described, a railway tie including a body portion provided with an abutment and formed to receive a clamping member, an anchoring member carried by the body portion, a clamping member carried by the tie and disposed to co-act with said abutment in engaging a rail, means slidably connected with said clamping member and operatively connecting the said member with the anchoring member, and means carried by the clamping member and slidably engaging said first mentioned means for maintaining the clamping member at its point of intersection with said first mentioned means, at substantially right angles thereto.

5. In a device of the character described, a railway tie including a body portion provided with an abutment and having an opening formed therein disposed to receive a

clamping member, an anchoring member carried by said body portion, a clamping member detachably engaging in said opening and including a body portion having a reduced shank formed thereon extending 70 through the opening and provided with a terminal head disposed to co-act with said abutment in engaging a rail, said body portion being apertured to receive a rod and having a guide lip formed thereon projecting laterally upon one side of the body portion and terminating, at its outer extremity, in a plane passing through the said aperture, a rod passing through said aperture and engaged upon one side by said guide 80 lip, said rod operatively connecting the clamping member with said anchoring member and being provided with a head, and resilient means surrounding the rod and bearing between the head thereof and the 85 body portion of the clamping member.

6. In a device of the character described, a railway tie including a body portion recessed upon one side and formed to receive a clamping member, the said body portion 90 being also provided with an abutment, an anchoring member carried by the body portion, a clamping member arranged upon the tie and projecting into said recess, said clamping member being disposed to co-act 95 with said abutment in engaging a rail, and adjustable means yieldably connecting the clamping member with said anchoring member and disposed in said recess.

7. In a device of the character described 100 a railway tie including a body portion provided with an abutment and formed to receive a rail clamp, an anchoring member carried by the body portion, a clamping member carried by the body portion and 105 disposed to coact with the said abutment in engaging a rail, means connecting the clamping member with the anchoring member, and a guide lug carried by said clamping member and operatively engaging said 110 means.

8. In a device of the character described, a railway tie including a body portion provided with an abutment and formed to receive a rail clamp, an anchoring member 115 carried by the body portion, a clamping member carried by the body portion and disposed to coact with the said abutment in engaging a rail, means connecting the clamping member with the anchoring member, and means carried by the clamping member and operatively engaging said first 120 mentioned means to provide a guide for the clamping member.

9. In a device of the character described, 125 a railway tie including a body portion provided with an abutment and formed to receive a rail clamp, an anchoring member carried by the body portion, a clamping member carried by the body portion and 130

1
disposed to coact with the said abutment in engaging a rail, means connecting the clamping member with the anchoring member, and a laterally projecting guide lug carried by the clamping member and freely engaging said means.

10. In a device of the character described, a railway tie including a body portion provided with an abutment and formed to receive a rail clamp, an anchoring member carried by the body portion, a clamping member carried by the body portion and disposed to coact with the said abutment in

engaging a rail, a rod connecting the clamping member with said anchoring member, ¹⁵ yieldable means bearing between the rod and the clamping member, and a guide lug formed on the clamping member and operatively engaging the rod.

In testimony whereof I affix my signature ²⁰ in presence of two witnesses.
